UNITED STATES PATENT OFFICE.

HENRY J. COERPER, OF INDIANAPOLIS, INDIANA.

RAIL JOINT.

Application filed August 23, 1926. Serial No. 130,923.

This invention relates to rail joints in which the opposing ends of the rails overlap and have their adjacent faces beveled so the tread surface of the rail at the joint is the same width as the rest of each rail; and the object is to provide a safer joint than that usually employed and one in which the passing wheels will pound less over openings due to contraction of the rails.

10. A further object is to provide a rail-joint with a positive shoulder-stop between the joined ends, such as can be easily made on the job by section men, and reduce the size of fish-plates and the number of bolts ordinarily required to join rail-ends as they are now connected.

The invention is fully shown in the accompanying drawing, in which—

Fig. 1, is a side elevation of the ends of rails when shaped and brought together to form a joint embodying my invention.

Fig. 2, is a cross section on the line 2—2 of Fig. 1.

Fig. 3, is a top plan view of the joined rails shown in Fig. 1, and

Fig. 4, is an underside plan view of the same parts shown in Fig. 3.

The numerals 5 and 6 designate two rails having their adjacent ends beveled on their inner surfaces on a diagonal line *a*—*b* extending entirely through the tread 7 and web 8, and through the base 9 from one edge at *a*, to the joint *b*, at an appreciable distance from the opposite edge of the base, and thence at right angles to the base edges at *c* in the edge of the base nearest to *b*. Contacting shoulders 10 and 11, are thus formed in base 9 which stop the movement of the rail-ends toward each other.

40. The above described bevels and shoulders can be easily formed by section men in making repairs by sawing a rail in two, beginning at *a* and sawing diagonally to *b*, and then from *c*, on the other side from the starting point *a*, in at right angles to intersection with the diagonal kerf at *b*.

A pair of fish-plates 12 and 13, are bolted, one on each side of the web 8, by bolts 14 and 15. The bolt-hole 16 in the fish-plates 50 are here shown as elongated to allow for expansion and contraction of the rails, under

varying temperatures, but the elongations may be made, instead, in the holes in the rails through which the bolts pass.

To counteract any tendency toward depression of the rails at the joints caused by the pounding of the car wheels, I prefer to provide a bridge-plate 17 to rest upon adjacent ties 18 between the ties and the rail-base under the rail-joint.

60. My improved joint as above described and as shown in the drawing reduces the wear on passing car wheels and the wear of the wheels on the rail joints; and the clicking sound incident to wheels passing over straight joints of ordinary construction is avoided because the load-shift from one rail to the other is gradual instead of abrupt.

Having thus described my invention, what I claim as new and wish to secure by Letters Patent, is—

1. A rail-joint comprising rail sections having the adjacent ends reversely beveled and lapped, the bevel on one side only of 75 the rail terminating in portions at an angle to the bevel forming shoulders adapted to contact with each other and limit the longitudinal movement of the rail sections toward each other.

2. A rail-joint comprising rail sections having the adjacent ends reversely beveled and lapped, the bevel on one side only of the rail terminating in portions at an angle to the bevel forming shoulders adapted to 85 contact with each other and limit the longitudinal movement of the rail sections toward each other, and a pair of fish plates between which the rail joint is bolted.

3. A rail-joint comprising rail sections 90 having the adjacent ends reversely beveled and lapped, the bevel on one side only of the rail terminating in portions at an angle to the bevel forming shoulders adapted to contact with each other and limit the longitudinal movement of the rail sections toward each other, a pair of fish plates between 95 which the rail joint is bolted and a bridge plate bridging a plurality of ties, upon which plate the rail-joint is supported.

100. In testimony whereof I affix my signature.

HENRY J. COERPER.
